UNITED STATES PATENT OFFICE.

WILLIAM ANDLER, OF CHICAGO, ILLINOIS.

DOOR CONSTRUCTION.

Application filed April 2, 1923. Serial No. 629,304.

To all whom it may concern:

Be it known that I, WILLIAM ANDLER, a citizen of the United States, and a resident of the city of Chicago, county of Cook, and 5 State of Illinois, have invented certain new and useful Improvements in Door Constructions, of which the following is a specification.

My invention relates to improvements in 10 door constructions and has for its object the provision of means for preventing warping of doors or straightening the doors after such warping has occurred.

Other objects will appear hereinafter.

15 The invention consists in the combinations and arrangements of parts hereinafter described and claimed.

The invention will be best understood by 20 reference to the accompanying drawings forming a part of this specification, and in which,

Fig. 1 is a face view of a door construction embodying the invention;

Fig. 2, an end view of the same;

25 Fig. 3, a detail view shown partially in section, of an attachment employed in the construction;

Fig. 4, a view similar to Fig. 1, but showing a modified form of construction; and

30 Fig. 5, an enlarged section taken on line 5—5 of Fig. 4.

The form of construction illustrated in 35 Figs. 1, 2 and 3 comprises an ordinary door having a truss construction attached thereto adjacent the free or swinging edge thereof. This truss construction comprises threaded rods 6 and 7, the rod 6 being threaded in a socket 9 on a bracket 10 secured to the upper edge of the door and the rod 7 being threaded in a socket 11 on a bracket 12, projecting outwardly from the central portion of the door. The rods 6 and 7 are connected by a turn buckle 8. Similar brackets 10 and 12 are also secured to the lower portion of 40 the door and connected by threaded rods 13 and a turn buckle 8. A handle yoke 14 is secured to the brackets 12 in position to span or pass around the door knob 15.

By this arrangement a reinforcing truss

is provided on the side of the door which is 50 expandible or contractable to exert a thrust or pull on the door to straighten the same in case the door has become warped as frequently happens.

In the form of construction illustrated in 55 Figs. 4 and 5 a door is illustrated equipped with a handle 16 in addition to the usual knob 15 and the connecting yoke 14 of the truss construction is omitted. Otherwise the construction is to all intents and purposes identical with that already described.

60 While I have illustrated and described the preferred form of construction for carrying my invention into effect, this is capable of variation and modification without departing 65 from the spirit of the invention. I, therefore, do not wish to be limited to the precise details of construction set forth, but desire to avail myself of such variations and modifications as come within the scope of 70 the appended claims.

Having described my invention what I 75 claim as new and desire to secure by Letters Patent, is:

1. The combination with a door, of threaded socket members having means for attachment to the flat upper and lower portions thereof adjacent the free edge of the door; brackets secured to the central portion of the door adjacent the free edge thereof and 80 provided with threaded sockets aligned with said first mentioned sockets in a plane at an angle to the plane of the door; rods threaded in said sockets, and turn buckles connecting said rods, substantially as described. 85

2. The combination with a door, of threaded socket members having means for attachment to the flat upper and lower portions thereof adjacent the free edge of the door; brackets secured to the central portion of the door and provided with threaded sockets aligned with said first mentioned sockets in a plane at an angle to the plane of the door; rods threaded in said sockets; turn buckles connecting said rods; and means connecting said central brackets, substantially 90 as described. 95

3. The combination with a door, of thread-

ed socket members secured to the upper and lower portions thereof, adjacent the free edge of the door; brackets secured to the central portion of the door and provided with threaded sockets aligned with said first mentioned sockets; rods threaded in said sockets; turn buckles connecting said rods; and a handle yoke secured to said

brackets and arranged to pass around the knob of the door, substantially as described. ¹⁰

In testimony whereof I have signed my name to this specification in the presence of a subscribing witness.

WILLIAM ANDLER.

Witness:

JOSHUA R. H. POTTS.
